(57) **CLAIM**

The ornamental design for a modular transit assist handle, as shown and described.

DESCRIPTION

FIG. 1 is a front elevation view of a modular transit assist handle of the present invention;

FIG. 2 is a side elevation view of a modular transit assist handle of the present invention;

FIG. 3 is a top plan view of a modular transit assist handle of the present invention;

FIG. 4 is an end view of a modular transit assist handle of the present invention;

FIG. 5 is also an end view of a modular transit assist handle of the present invention; and,

FIG. 6 is a bottom view of a modular transit assist handle of the present invention.
